(57) CLAIM

The ornamental design for a jacket as shown and described.

DESCRIPTION

FIG. 1 is a side perspective view of a jacket with my new sleeve design;

FIG. 2 is a front view thereof; and,

FIG. 3 is an enlarged detail side view of the jacket showing the new sleeve design.

The dashed lines in the figures showing a partial human figure illustrate the environment in which the article is used and do not form a part of the claimed design. The dashed lines in the figures on the jacket show unclaimed features of the jacket and do not form a part of the claimed design. The long dash, short dash, long dash, broken lines encircling the enlarged view of FIG. 3 define the bounds of the enlarged detail view and form no part of the claimed design.
